UNITED STATES PATENT OFFICE.

ERNST GOTTHILF BRACK, OF WINTERTHUR, SWITZERLAND.

APPARATUS FOR PREPARING AND MULTIPLYING LIGHT COPIES.

Application filed March 5, 1923. Serial No. 822,967.

To all whom it may concern:

Be it known that I, ERNST GOTTHILF BRACK, a citizen of the Republic of Switzerland, residing at Winterthur, Breitestrasse 7, in the Canton of Zurich, Republic of Switzerland, have invented certain new and useful Improvements in Apparatus for Preparing and Multiplying Light Copies, of which the following is a specification.

10 The object of this invention is to provide apparatus whereby clear images may be secured from living plants. The method of carrying this out comprises the spreading out of a living plant or parts thereof with a slight pressure, preparing from this plant in a single continued exposure a negative on a sensitive paper such as heliography paper which does not unfavorably change even when exposed a long time and producing from this negative any number of positive copies in any color upon a sensitive fabric.

15 In the apparatus for executing the method, a flexible carpet having flexible filaments is provided and arranged in a heliography printing frame, for inserting and holding a spread plant and for tightly snugging the sensitive paper to the plant.

20 The accompanying drawing shows one constructional example of the apparatus according to the invention, like numerals indicating like parts throughout and in which—

25 Figure 1 is an elevation of the printing frame,

Fig. 2 is a rear view also in elevation of Fig. 1,

Fig. 3 is a plan view,

Fig. 4 is a sectional view on line X—X of Fig. 2,

Fig. 5 is a sectional view similar to Fig. 4 showing a sensitized paper in place,

Fig. 6 is a similar sectional view showing a method of applying the carpet, and

Fig. 7 is a sectional view similar to Fig. 5.

The apparatus shown on the drawing comprises a solid wood frame F, a glass plate E, a biparted cover A, two holding bars G for holding the inserted plant P and the negative paper D without pressure, and a flexible

carpet B having lead filaments. The inclined guides by means of the bars G hold the cover A in position.

When a plant P is to be printed, an extra thin sensitized negative heliography paper D that is the usual "sepia" paper which does not unfavorably change even when exposed a long time, is laid with the sensitive face on the inner side of the glass E. The carpet B with the lead filaments is then laid upon the paper B and both are rolled back. Hereupon the plant is pushed with its lower end under the roller B D. Then the parts of the plant adjacent to the roller B D are brought in that position on the glass plate which is desired in the image, whereupon the carpet is suitably unrolled together with the negative paper. The weight of the lead carpet insures an equal pressure and will snugly hold the paper to the plant and the plant to the glass plate. When the plant has been carefully inserted, the apparatus is closed by means of the cover A and the bars G, but without exerting a sensible pressure. Then the negative is exposed to any suitable light rays until even the finest structural parts of the plant begin to be marked. When the exposure is sufficient, the copy is removed from the apparatus, developed, fixed and dried, and will then be ready for printing any number of positives. Figs. 5 and 7 show how a positive paper T is inserted and printed in the frame A.

It is however understood that any suitable material can be used for the carpet and that any objects can be printed which can be adapted to a printing frame. The essential feature of the flexible carpet is that its weight will exert equal pressure at all points.

I claim as my invention:

1. A flexible carpet for photographic apparatus having heavy flexible filaments thereon.

2. In an apparatus for preparing photographic images, a flexible carpet having flexible filaments adapted to be arranged in a heliography copying frame, for inserting and holding a plant and for tightly snugging the sensitive paper to the plant by means of the weight of said carpet.

3. A flexible carpet for photographic apparatus having flexible metallic filaments thereon.
4. A flexible carpet for photographic apparatus having flexible lead filaments thereon.
5. An apparatus for preparing plant images comprising a frame provided with a glass plate; a flexible carpet having flexible filaments thereon adapted to exert equal pressure by weight at all points against said

glass plate for inserting and holding a plant and for tightly snugging the sensitive paper to the plant by means of the weight of said carpet; and a cover for said frame.

15

In testimony whereof I have affixed my signature in presence of two witnesses.

ERNST GOTTHILF BRACK.
